UNITED STATES PATENT OFFICE.

JOHN M. HOPWOOD, OF PITTSBURGH, PENNSYLVANIA.

WALL SECTION FOR FORMING BAFFLES IN BOILERS.

Application filed April 28, 1922, Serial No. 557,193. Renewed October 13, 1923.

To all whom it may concern:

Be it known that I, JOHN M. Hopwood, residing at Pittsburgh, in the county of Allegheny and State of Pennsylvania, a citizen of the United States, have invented or discovered certain new and useful Improvements in Wall Sections for Forming Baffles in Boilers, of which improvements the following is specification.

10 In order that the hot gases may contact to the greatest possible extent with the tubes of a horizontal water tube boiler, the tubes are so arranged that tubes of one row will be in line vertically with the spaces between 15 tubes of adjacent rows and hence spaces between tubes are irregular in shape and so narrow that it is exceedingly difficult to form a baffle at right angles to the tubes with blocks of refractory material, and 20 hence resort has been had to build a baffle in situ. The method employed consisted in forming a mold consisting of two side walls spaced a distance apart equal to the desired thickness of baffle and arranged at 25 right angles to the tubes which extend through these side walls. On account of the narrow spaces between adjacent tubes, only narrow strips of wood could be used and on account of the inaccessibility of the inner 30 tubes, it was impractical to so fit the strips around the tubes and against one another to make tight joints and consequently when the material for the baffle is made sufficiently fluid to flow around the tubes and fill all 35 spaces between the walls, water would escape carrying with it the fluxing ingredient of the material, and hence when the material was dried out and subjected to a high heat, the baffle would crumble away. In 40 order to prevent the loss of fluxing ingredients, the material for the baffle has been made less fluid, and in order to ensure the complete filling of the mold and enclosure of the tubes, the material was puddled to 45 cause the material to settle down around the tubes. But as the sides of the mold were weak due to the conditions under which they were formed, the lateral pressure resulting from the puddling caused an opening up of the mold walls and a consequent 50 escape of material. And further, unless the puddling is done skillfully and thoroughly, there will be openings through the baffles,

such openings usually occurring immediately below the tubes.

The object of the invention described herein is to provide collapsible wall sections, which can be inverted between the tubes and then extended or enlarged thereby causing its edges to partially surround the tubes, and portions to project between tubes and form a tight joint with the tubes and edges of adjoining wall sections. The invention is hereinafter more fully described and claimed.

In the accompanying drawings forming a part of this specification, Fig. 1 is a sectional view showing a portion of the sections forming a wall across the tubes in position; Fig. 2 is a plan view on an enlarged scale showing the manner of forming a monolithic baffle; Fig. 3 is a side elevation on an enlarged side of a wall section; Fig. 4 is a sectional view on a plane indicated by the line IV—IV, Fig. 3; Figs. 5, 7, and 9 are views similar to Fig. 3, illustrating different embodiments of the improvements claimed herein; Figs. 6, 8, and 10 are sectional views on planes indicated respectively by lines VI—VI, Fig. 5, VIII—VIII, Fig. 80 7, and X—X, Fig. 9.

In the practice of my invention the mold for forming a monolithic baffle consists of two walls extending transversely of the tubes, said walls fitting around and forming tight joints with the tubes. Each of these walls consists of a plurality of members, each member being so constructed that its longitudinal edge portions, which, when the members are in position, should contact with the tubes and edges of adjoining sections when the walls are to be adjusted in position, may be moved towards each other thereby so reducing the transverse dimensions of the sections as to permit of their sliding to their longitudinal position between the tubes, and moved apart to bring the members into operative relation to the tubes. This reduction of the members in transverse dimensions may be effected in many ways as for example, by so constructing the longitudinal edge portions of the sections that they may be collapsed or expanded by constructing the members in two longitudinal sections which may be moved transversely relative one to the other or

may be hinged together, permitting the parts to be folded one upon the other. The several embodiments above referred to of the improvement claimed herein will be 5 hereinafter more fully described and claimed. It should be, premised, however, that the terms "collapsing" or "collapsible" are used herein in a broad sense and as covering any construction whereby the distance between the longitudinal edges of the wall members may be varied.

In the construction shown in Figs. 1, 2 and 3, the wall members are formed with a rigid body portion consisting of two strips 15 of metal or other suitable material having circular notches 2 in their opposite edges, the positions of the notches being dependent on the relative arrangement of the tubes of the boiler. The longitudinal edge 20 portions of the sections consist of collapsible tubes 3, which in the construction shown, are formed by folding a strip of rubber or other suitable material on its self and clamping the edges together between the 25 strips 1 which are secured together by rivets or other suitable means. These tubes are closed at one end and are provided at their opposite end with nipples 4, similar to those employed in connection with the inner tubes 30 of pneumatic tires.

When building baffles, two series of wall sections are passed between diagonal rows of tubes with the sides of the members parallel or approximately parallel with the 35 tubes. When a member has reached the proper longitudinal position it is turned on its longitudinal axis to a position at right angles to the boiler tubes. The 40 tubular edges 3 are then inflated causing them to bear against the boiler tubes and against the tubular edges of adjoining wall members, as clearly shown in Figs. 1 and 2. The two series of members are spaced a suitable distance apart, as shown in Fig. 2, 45 dependent on the required thickness of the baffles, and the bottom of the space between the walls is closed by a board or any other suitable means, and the ends of the spaced wall section are closed by the side walls 50 of the boiler setting. As all joints between the members and the tubes and edges of adjacent members are tight, being formed by the tubular edges or portions of the members, the material composing the baffles 55 can be made so fluid that it will completely fill all parts of the mold thus formed by the walls, and as there cannot be any escape of water there will be no loss of the fluxing material and all parts of the 60 monolithic structure will be uniform as regards its heat resisting qualities.

In the form shown in Figs. 5 and 6 the body portions of the wall sections consist of two overlapping strips 6 of metal or other 65 suitable material adapted to move laterally

one over the other. These strips are provided with transversely inclined slots 8 and 9, those in one strip or section being at an angle to those in the other. Pins 10 secured to a longitudinally movable rod 11, 70 project into the slots in both strips or sections so that by a longitudinal movement of the rod the strips will be shifted laterally thereby changing the transverse dimensions of the member. The section or strips are 75 held from relative longitudinal movement by pins 12 passing through horizontal slots 13 in the section or strips.

In lieu of employing pins engaging oppositely inclined slots to vary the widths of the wall members, toggle joint devices 80 may be employed as shown in Figs. 7 and 8. These devices consist of links 14 showing their respective ends pivotally connected to the sections or strips and their opposite ends pivotally connected to the longitudinally movable rod 15. Independent longitudinal movements of the plates or strips may be prevented in any manner as for example by slots 13 in the plates and pins 12 passing 90 through said slots.

As shown in Figs. 9 and 10, the metal strips or sections 6 may be hinged together so that one strip or section may be folded one upon the other, inserted between the tubes and then spread apart until the sections are in alinement transversely. A suitable lock, as for example a latch 16, pivoted to one strip and adapted to pass behind a lug 17 on the other strip, may be employed 100 for preventing an accidental collapsing or folding of the strips.

As the collapsing or changing in width of the wall members is effected in the forms shown in Figs. 5 to 10 by the relative movements of the plates or strips forming the body portions sections, inflatable edge portions are not necessary as in the construction shown in Figs. 1 to 4, and hence resilient packing such as solid or hollow strips 105 18 may be used as a packing along the outer edges of the plates or strips, as shown in Figs. 5 to 10. It will be understood that the outer edges of the strips or sections are 110 provided with circular notches 2 for the reception of the boiler tubes when the wall sections are placed in position.

I claim herein as my invention:

1. A member for forming molds for shaping baffles in boilers having in combination a body portion and yielding edge portions and means for changing the transverse dimensions of one of said parts.

2. A member for forming molds for shaping baffles in boilers, having a body portion having circular notches in opposite edges for the reception of the boiler tubes and strips of yielding material along the notched edges and means for changing the transverse dimensions of one of said parts.

3. A member for forming molds for shaping baffles in boilers having in combination a body portion and tubular edge portions adapted to be inflated to form tight joints with adjacent surfaces.

4. A member for forming molds for shaping baffles in boilers having in combination a body portion having its opposite edges notched for the reception of the boiler tubes

and tubes arranged along the edges of the 10 body portion and adapted to be inflated to form tight joints with the tubes and with portions of adjacent sections projecting between the tubes.

In testimony whereof, I have hereunto set 15 my hand.

JOHN M. HOPWOOD.
